CHILD'S VEHICLE

Cecil Arthur Rassier, Erith, England, assignor to
D. Sebel & Company Limited, Erith, England

Filed Apr. 2, 1958, Ser. No. 50,290

Term of patent 14 years

(Cl. D34—15)

Figure 2 is a side perspective view thereof the opposite side having substantially the same appearance; and

I claim:

The ornamental design for a child's vehicle, as shown and described.
